UNITED STATES PATENT OFFICE.

OSCAR MEYER, OF CHICAGO, ILLINOIS.

PRINTING-PLATE HOLDER.

Application filed August 14, 1925. Serial No. 50,186.

The present invention is a continuation in part of my pending application for U. S. Letters Patent Ser. No. 13,977, filed March 9, 1925.

5 An object of the present invention is to provide means for attaching printing plates to the cylinder segment carrying the printing plate of so-called multigraph printing machines and other printing devices or 10 presses wherein printing plates are to be temporarily secured to the segment.

It will be understood that the present invention is capable of varied expression; particularly as adapted to use in the various 15 branches in the printer's and other arts, so that the illustrations and descriptions thereof herein are to be understood as merely exemplary, and therefore not exhaustive. The subjoined claims will define its scope, in view 20 of the modifications and adaptations which may be made by those who practice the arts to which it is adaptable.

Heretofore, so far as I am aware, the curved printing plates, such as have been 25 used with what are known under the trade name of "multigraph printer's machines" have been provided with solid T-shaped radial projections, which latter projections are adapted to register laterally with suitable 30 T-slots in the periphery of the segment, the said T-shaped projections being integral with the printing plate. By my present invention I obviate using the solid T-shaped projections; using in place thereof 35 projections formed from sheet metal or the like and, therefore, more or less resilient laterally with respect to said projections, in order to insure that the projections will adapt themselves to the T-slots of the platen 40 more readily than would a solid material projection. This resiliency is desired in case of inaccuracy in manufacture affecting the spacing of the projections as well as to their form with respect to the T-shaped slots 45 with which the projections cooperate, though their shapes may not exactly register. In the exemplified form, the slots are T-shaped, while the projections are generally like so-called T-rails. The said projections 50 in one form shown in the drawings (Figs. 1 and 2) appear as radial clips extending from the printing plate.

Manufacturing advantage obtained by the present invention is, therefore, that a greater tolerance is admissible, which, of course,

operates to lessen labor cost in making the completed printing plates.

The present invention, as applied to multi-graph plates referred to, will differ in details from its application to printing plates 60 of large dimensions, such as are used in commercial presses for printing newspapers, books and large output matter, wherein the printing plates are made of thicker material.

With reference to the accompanying sheet 65 of drawings:-

Fig. 1 shows an end view of a cylinder segment of a form of printing device generally known as a "multigraph printing machine". It also shows the printing plate in 70 place.

Fig. 2 shows a fragmentary portion of the periphery of parts viewed from the side as shown in Fig. 1, enlarged to make the details of the slots and cooperating radial projections or clips more distinct.

Fig. 3 shows a perspective view of the key used to attach the printing plate to the cylinder segment, the end view of which is shown in Fig. 2.

Fig. 4, shows a modification of Fig. 2 wherein the key has a compression bolt and wherein the key self-adjusts itself.

Fig. 5 shows a side view of the key shown in Fig. 4 which is a modification of the 85 key shown in Fig. 3 wherein the compression bolts are shown at each end arranged to draw the wings of the key together so that the key may be freely inserted into the dovetail slot and the bolt thereafter 90 turned to permit the wings of the key to flex outwardly to adapt themselves to the dovetail slot in the manner as will appear.

Fig. 6 shows an end view of the key shown in Figs. 4 and 5 wherein the bolt of one end 95 is in view.

Fig. 7 is a plan view of the key shown in Figs. 4 to 6.

The T-shaped slots 7, which are formed between adjacent T-shaped projections 8 are 100 equally spaced over the periphery of the cylinder segment 9. The dovetail slots 10 of the printing plate 11, which receive the key shown in Fig. 3, are spaced a multiple 105 of the radial angle between the T-shaped slots 7; being five times the radial angle between the T-shaped slots 7 of the platen segment 9, in the exemplified form. This angle may be varied depending upon the size of the printing plate, though the dovetail slots 110

10 in the printing plate will preferably be a multiple of the radial angle between the T-shaped slots in the periphery of the cylinder segment.

5 In the first stages of manufacture of the printing plate 11 there are no radial projections for attaching the plate; these projections are applied later and as a final operation. Accordingly, a dovetail groove 10 is milled or planed laterally of the inside curvature of the plate; in fact the groove 10 may have a convex form at its bottom, generally conforming with the curvature of the plate. Moreover, the groove 10 may have 15 sides which are not obliquely angled with the bottom of the groove so that the groove will not then be dovetail in form. However, I prefer to make the grooves 10 dovetail in form, to improve the mechanical 20 union and adaptation of the key to the groove. The dovetail groove 10 in Fig. 2 in the drawings is shown relatively deep to the thickness of the sheet material of the key. Where the plate is made of thin material, as is usually the case in plates used for 25 multigraph printing machines, the depth of the groove for receiving the key will not be appreciably deeper than the thickness of the sheet material of the key.

30 The key Fig. 3 is made of sheet material which preferably has the quality of resilience so that its crown will flex with its web portion. The wings 12 together with the folded web portion 13 and the crown portion 14 have the general exterior appearance of a so-called T-rail referred to. The outer edges of the wings 12 may be beveled as shown in Fig. 3 to angularly register with the dovetail groove 10, but this is not 35 essential, since the sheet material of the key is thin enough to fit into the dovetail groove 10 by applying the key endwise with slight force to overcome the friction which is occasioned by the resilience of the edges of the 40 wings of the key due to the wings having a normal spread somewhat greater than the maximum width of the dovetail groove. When the key is forced into its position in the dovetail groove 10 it cannot be 45 readily removed by force applied radially because to do this the resilience operating to spread the wings 12 and the attendant friction along the sides of the dovetail groove 50 will operate against this. That is, the key will resist being withdrawn radially from the dovetail groove containing it, though due to its resilience at the web portion 13 it will permit lateral movement of the crown portion without unseating the wings 12 55 from the groove. In order to make the key more secure in the dovetail groove of the printing plate, a cement or other adhesive may be applied into the groove before inserting the wings of the key. Moreover, 60 after the key is in place, the overhanging 65

or abutting side seams formed by the co-operated key and dovetail groove may be calked or flanged over to make a more permanent mechanical union between the key and plate.

If when the printing plate is applied to the cylinder segment by registering the radial clips (usually two) formed by the keys with the T-shaped slots of the segment, there is a slight disalignment, the crowns of 70 the disaligned clips will flex on their webs sufficiently to permit the printing plate to be laterally applied and held sufficiently rigid. That is, the clips of my invention adapt themselves to a certain degree and 75 moreover, obviate play or looseness as is occasioned with ill-fitting clips where no automatic or self-adjusting fitting is provided between them and the T-slots.

In this connection, it will be understood 80 that it is only required that the crown of the clip shall have a clasp or resilient shoulder engagement. Thus, the printing plate would be snugly retained if but one shoulder of the crown of the clip were making contact with a T-projection or if the crown were designed to make contact under a single shoulder thereof because of one shoulder of the clips being omitted.

In applying the invention to printing plates having considerable thickness, the dovetail slots may be given a greater depth and the key inserted without adhesive after the printing plate has been loosely applied to the periphery of the cylinder segment. 90 The wings 12 of the key shown in Fig. 2 will then serve to adjust the key with reference to the dovetail slot and the registering T-shaped slot, though said slots are not exactly aligned due to inaccuracy in manufacture; however they will retain the plate rigidly enough for operative purposes.

The modification of the key shown in Figs. 5, 6 and 7 lends itself to the uses illustrated by Fig. 4, wherein the screw bolts 110 15' having a threaded union with one of the opposite webs 13' may be turned so as to draw the shoulder of the bolt head to flex the webs 13' inwardly so that the wings 12' 115 may be freely inserted into the dovetail slot 10' while the crown of the key slides loosely into the T-shaped slot 7'. After two or more of the keys have been placed, one for each pair of registering dovetail slots and T-shaped slots, the bolts 15' will be loosened 120 to admit of the keys seating themselves responsive to their resilience now unrestrained by the respective bolts. In withdrawing the keys shown in Figs. 5, 6 and 7, the bolts will first be set up to overcome the resilience 125 of the webs of the key whereupon the key will have play and may thus be freely removed so that the printing plate will thereby become free. The invention as applied as in Fig. 4 thus affords a self-adjust- 130

ing link for attaching a printing plate or the like to a cylinder and which link may be readily removed.

I claim:

- 5 1. A printing plate, comprised of a stereotype plate having ribs of flexible material made rigid with the plate for registry with slots of a printing cylinder for thereby securing the printing plate to the cylinder.
- 10 2. A printing plate, comprised of a stereotype plate having resilient ribs of thin sheet material made rigid with the plate for registry with the slots of a printing cylinder for thereby securing the printing plate to the cylinder.
- 15 3. A printing plate, comprised of a stereotype plate having resilient ribs of thin sheet material folded upon itself and made rigid with the plate for self-adjusting registry with the slots of a printing cylinder for thereby securing the printing plate to the cylinder.
- 20 4. In a printing mechanism, a printing plate comprised of a stereotype plate, ribs of thin sheet material made rigid with the plate, a printing cylinder for holding the plate, dovetail slots lengthwise of the cylinder whereby the printing plate may be applied and removed from the cylinder in which the ribs cooperate with the slots and wherein due to the flexibility of the thin ribs the plate will become securely adjusted into fitting position with respect to the cylinder notwithstanding that the ribs as positioned on the plate do not exactly register with the slots of the cylinder.
- 25 5. In a printing mechanism, a printing plate comprised of a curved stereotype plate, ribs of thin sheet material made rigid with the plate, a printing cylinder for holding the plate, dovetail slots lengthwise of the cylinder whereby the printing plate may be applied and removed from the cylinder by sliding the plate lengthwise of the cylinder and wherein due to the flexibility of the thin ribs the plate will become securely adjusted into fitting relation with respect to the periphery of the cylinder notwithstanding that the ribs as positioned on the plate

do not exactly register with the slots of the cylinder.

6. In a printing mechanism, a printing plate comprised of a stereotype plate, ribs of thin sheet material made rigid with the plate, a holder for the plate, dovetail slots of the holder whereby the printing plate may be applied and removed from the holder in which the ribs cooperate with the slots and wherein due to the flexibility of the thin ribs the plate will become securely adjusted into fitting relation with respect to the surface of the holder notwithstanding that the ribs as positioned on the plate do not exactly register with the slots of the holder.

7. In a printing mechanism, a printing plate comprised of a stereotype plate, ribs of thin sheet material made rigid with the plate, a holder for the plate, slots of the holder cooperative with the ribs of the plate whereby the printing plate may be applied and removed from the holder by a movement parallel with the lengthwise direction of the ribs and wherein due to the flexibility of the ribs the plate will become securely adjusted into fitting relation with respect to the surface of the holder notwithstanding that the ribs as positioned on the plate do not exactly register with the slots of the holder.

8. In a printing mechanism, a printing plate comprised of a stereotype plate, ribs of thin sheet material having resilience and made rigid with the plate, a holder for the plate, dovetail slots of the holder cooperative with the contour of the ribs of the plate whereby the printing plate may be applied and removed from the holder by a movement parallel with the lengthwise direction of the ribs and wherein due to the flexibility of the ribs the plate will become securely adjusted into fitting relation with respect to the surface of the holder notwithstanding that the ribs as positioned on the plate do not exactly register with the slots of the holder.

In witness whereof, I hereunto subscribe my name this 12th day of August, 1925.

OSCAR MEYER.
